UNITED STATES PATENT OFFICE.

AUGUST H. PAPE, OF KENTFIELD, CALIFORNIA.

FUEL-SUPPLY FOR INTERNAL-COMBUSTION ENGINES.

1,344,815.

Specification of Letters Patent. Patented June 29, 1920.

Application filed March 4, 1919. Serial No. 280,547.

To all whom it may concern:

Be it known that I, AUGUST H. PAPE, a citizen of the United States, residing at Kentfield, in the county of Marin and State of California, have invented new and useful Improvements in Fuel-Supplies for Internal-Combustion Engines, of which the following is a specification.

The object of the present invention is to provide an apparatus whereby a limited, comparatively small, quantity of fluid fuel, as for instance, gasolene, may be supplied to an inlet manifold of an internal combustion engine, and such that, while such supply is being made, the main source of supply may be automatically cut off, thereby preventing waste of the fluid fuel due to carelessness or forgetfulness on the part of the operator of the device, said main supply being automatically renewed when the supply to the engine is cut off.

In the accompanying drawing, Figure 1 is a broken side view of my improved device; Fig. 2 is a detail side view of an operating disk.

Referring to the drawing, 1 indicates a main tank for containing fluid fuel such as gasolene, and 2 a comparatively small tank for containing only the quantity of gasolene which is necessary at one time. It is becoming more and more the practice to operate internal combustion engines by distillate or other oil heavier than gasolene, but when such operation is in use, it is frequently necessary or desirable, as for instance in starting the engine, or when a long hill is to be surmounted or in traveling over soft ground, or when from some other cause the engine appears to be failing, to be able to supply a small quantity of gasolene, either in addition to, or in place of, the ordinary fluid fuel such as distillate. The present contrivance enables this small quantity of gasolene to be supplied, and at the same time, shuts off the main supply of gasolene so that should the operator, after turning on the gasolene, forget to turn it off, no more than a certain small quantity of gasolene would be consumed, and also enables the small receptacle 2 for gasolene to be automatically replenished when the supply to the engine has been cut off.

The small tank 2 is secured to the bottom of the main tank 1 and has, extending from its upper side through the bottom of said main tank 1, apertured bosses 3, 4, leading

into said tank 2. Connecting with the aperture in the boss 3, is the lower end of a vertical pipe 6 which leads through the top of the main tank 1. To its upper open end is pivoted as shown at 7, one end of a lever 8, which extends through diametrically opposite slots 9 in the upper terminal portion of a tube 10 slideable vertically in a tube 11, the lower end of which is secured to the boss 4 and communicates with an aperture 12 therein leading into the tank 2 while the upper end extends through the top of the tank 1. The lower end of the tube 10 is secured to a conical valve 13, which controls the passage into the aperture 12 of gasolene flowing from the main tank 1 through a lateral aperture 14 into the lower end of the tube 11.

To the free end of the lever 8 is pivotally connected the upper end of a stem 15 which can slide vertically in guides 16 secured upon an end of the main tank 1, the lower end of said stem resting upon the periphery of a disk 17 which has diametrically opposite holes 18 therethrough. Through said holes 18 extend the tines 19 of a forked end of a handle 21 which extends through the dash 22 of the automobile and is formed behind said wind-shield with a handle 23. One of said tines 19 is secured to said disk 17 by a cotter-pin 24. Thus the disk can be turned about its axis by operating the handle 23. By turning said disk a cam or hump 26 on its periphery is adapted to engage the lower end of said stem 15 and raise the same, as shown in Fig. 2, thereby, through the medium of the lever 8, raising the conical valve 13 from its seat and admitting gasolene from the main tank 1 into the small tank 2. Through a central threaded hole 27 in the disk 17 is screwed a threaded portion of a stem 28 of a needle valve 29, and after said valve 29 has been properly adjusted to its seat, said stem is locked in said disk by means of a lock-nut 31. Another threaded portion 32 of said stem is screwed into a T-shaped valve casing 33, said stem passing through a stuffing box 34 secured upon an end of said valve casing 33, and, by reason of the engagement of the threaded portion 32 of the stem with the internally threaded portion of the valve casing, the rotation of the stem causes the needle valve 29 to move to or from its seat. Said casing is screwed into a boss 36 extending from the small tank 2 and has a

conduit 37 communicating with a conduit 38 leading from said tank 2 in said boss 36, so that said needle valve controls the escape of gasoline through said conduits from said 5 tank 2. If the gasoline be permitted to pass the valve 29, it flows through a conduit 39 in a central member of said T-shaped casting and into the upper end of a flexible pipe 41, said upper end being connected with said T-shaped casting through 10 a stuffing-box 42. The lower end of said flexible tube communicates with the inlet manifold 43 of the engine.

The parts are so arranged, that when the 15 handle 23 is turned so as to raise the conical valve 13 from its seat and permit gasoline to flow from the main tank 1 to the small tank 2, the needle valve 29 is closed so that no gasoline can escape from said tank 2. It 20 is to permit the gasoline to flow into said tank 2 from the tank 1 that the pipe 6 is provided, since it allows the air to escape from said tank 2 as gasoline flows thereinto. When the handle 23 is turned to withdraw 25 the cam-shaped portion 26 of the periphery of the disk 17 from the bottom of the stem 15, said stem drops and the conical valve 13 drops, cutting off the flow of fluid fuel from the tank 1 to the tank 2. At the same time 30 the rotation of the disk 17 causes the needle valve 29 to be withdrawn from its seat and allows gasoline to flow from the tank 2 through the pipe 41 and into the inlet manifold of the engine, this flow being permitted 35 by reason of the tank 2 being open to the atmosphere through the pipe 6. However, only the quantity of gasoline in the tank 2 can flow to the inlet manifold. When the operator again closes the outlet from the 40 tank 2, he automatically opens the inlet to the tank 2 and the valve 13 and thus the tank 2 is again replenished from the tank 1.

While the apparatus is primarily designed 45 to allow only a small quantity of gasoline to be supplied at one time to the engine, yet it may be desirable to supply a constant stream of gasoline of small volume to be added to distillate to enrich the fuel. This is done by forming the latter half of the 50 periphery of the disk, which comes in contact with the bottom of the pin 15, of a radius gradually increasing until the periphery of the disk coincides with the top of the hump 26. In this way, on turning the disk 55 17 through any angular distance considerably less than a semi-circle, the valve 13 will remain closed, but on turning it more through a semi-circle the valve 13 will be

raised to an extent gradually increasing, so that any quantity of gasoline desired, can, 60 by proportionately turning the disk 17, be caused to flow from the tank 1 into the tank 2 and thence to the engine. The stream of gasoline thus permitted to flow is so small that it draws with it a small quantity of air 65 through the tube 6, so that air is permitted to enter the enriched mixture.

I claim:

1. In combination with main and auxiliary receptacles for fluid fuel, having communication between them, the auxiliary tank communicating with the combustion chamber of an internal combustion engine, means operated at will, for simultaneously opening either of said communications and closing the other and when desired, opening both communications simultaneously, said means maintaining the communications established and cut off without necessitating the manual holding thereof.

2. In combination with an inlet manifold of an internal combustion engine, a main tank for containing fluid fuel, an auxiliary tank for containing a small supply of fuel having a communication with the main tank, 85 a valve for controlling the communication between the tanks, a conduit leading from the auxiliary tank to said inlet manifold, a valve for controlling said conduit and means for simultaneously opening either of said 90 valves and closing the other including a rotatable member which when rotated a predetermined amount will open one valve and close the other and remain in such position to maintain the valves opened and closed 95 respectively and means for rotating said member.

3. The combination with an inlet manifold of an internal combustion engine, of a main tank for containing a fluid fuel, an auxiliary 100 tank for containing a small supply of fuel and having a communication with said main tank, a valve for controlling the flow of fuel from one tank to the other, a conduit leading from the auxiliary tank to the intake manifold, a valve for controlling the flow of fuel through said conduit and which when rotated will move toward or away from closing position, a cam connected with and for rotating said last named valve, operative 105 connections between the first named valve and cam whereby when said cam is moved either of said valves will be simultaneously opened and the other closed and means for rotating said cam.

AUGUST H. PAPE.
